UNITED STATES PATENT OFFICE

ALBERT H. AMMANN, OF CHICAGO, ILLINOIS, ASSIGNOR TO JOSTAM MANUFACTURING CO., OF CHICAGO, ILLINOIS, A COPARTNERSHIP COMPOSED OF W. D. STANNARD AND A. H. AMMANN

RECOIL PAD FOR GUNS

Application filed September 3, 1929. Serial No. 389,953.

The present invention relates to recoil pads for guns and is particularly concerned with improvements in the type of recoil pad having a relatively hard base plate for attachment to a gun stock, and a relatively soft rubber cushion carried by the base plate for engagement with the shoulder of the mechanism.

One of the most important objects of the invention is the provision of a recoil pad in which the resiliency or cushioning effect may be conveniently adapted to suit the needs of each individual marksman, preferably without changing the external appearance or other characteristics of the recoil pad.

Another object of the invention is the provision of recoil pads for guns having a relatively stiff supporting member, a relatively soft shoulder engaging member, and an intermediate cushioning structure, the characteristics of which may be varied at will to adapt the recoil pad to the individual "feel" of the marksman at any point of engagement with his shoulder.

Another object of the invention is the provision of a recoil pad of the class described which is provided with a plurality of intermediate cushioning devices of graduated length, adapted to come into operative engagement with other parts of the pad at different stages of distortion of the pad, to produce a pad of predetermined characteristics.

Another object is the provision of a recoil pad having a plurality of air pockets, the air volume of which may be regulated to change the characteristics of the recoil pad to suit the individual needs of any marksman.

Another object is the provision of a recoil pad in which the resiliency may be controlled or predetermined by the combined effect of pneumatic pockets and other resilient devices adapted for successive operation at different stages of distortion of the pad.

Other objects and advantages of the invention will be apparent from the following description and from the accompanying drawings in which similar characters of reference indicate similar parts through the several views.

Referring to the drawings of which there are two sets:

Figure 1 is an elevational view showing the recoil pad of the present invention applied to a gun stock;

Figure 2 is a rear elevational view of the recoil pad of Figure 1;

Figure 3 is a sectional view of the pad and stock taken on the plane of the line 3-3 in Figure 2 looking in the direction of the arrows;

Figure 4 is a sectional view taken on the plane of the line 4-4 of Figure 3 looking in the direction of the arrows;

Figure 5 is a sectional view taken on the plane 5-5 of Figure 2 looking in the direction of the arrows;

Figure 6 is a view similar to Figure 3 of a modified form of the invention; and

Figure 7 is a view similar to Figure 4 of the same modification taken on the plane of the line 7-7 of Figure 6.

Referring to Figures 1 to 5, 10 indicates a conventional gun stock which may be provided with a recoil pad, indicated in its entirety at 11, of a size adapted to substantially fit the end of the gun stock 10.

In the embodiments which have been chosen to illustrate the invention the recoil pad 11 preferably consists of a supporting member 12 of relatively stiff material, a shoulder engaging member or cushion 13 and an intermediate cushioning device 14. However, it should be understood that in some embodiments of the invention the supporting member, shoulder engaging member, and intermediate cushioning device may all be constructed of an integral piece of material.

In the preferred embodiment the supporting member 12 consists of a relatively stiff plate of hard rubber, the outer boundary 15 of which conforms substantially to the shape of the gun stock 10. The supporting plate 12 is provided with a plurality of countersunk apertures 16 adapted to receive wood screws 17 for attaching the supporting plate 12 to the gun stock 10. The shoulder engaging portion 13 of the recoil pad 11 preferably consists of relatively soft rubber, the outer

boundary 18 of the shoulder engaging member also conforming substantially to the shape of the end of the gun stock 10. The shoulder engaging member 13 is provided with a laterally curved or convex rear surface 19, giving the extreme edges 20 of the shoulder engaging member greater flexibility to prevent any possibility of undesirable rigidity at the rear corners of the pad.

0 The intermediate cushioning device 14 preferably consists of a relatively flat body of resilient material, such as sponge rubber, having an outer surface 21 which also conforms substantially to the shape of the gun stock 10 supporting plate 12 and shoulder engaging member 13.

Where the gun stock 10 is provided with a taper, the shape of the recoil pad 11 is preferably such that it forms a continuation of the gun stock 10 along the same line of taper as shown in Figures 1 and 2. Thus the intermediate cushion 14 and the shoulder engaging member 13 are each slightly longer than the supporting plate 12, the lower outline 22 forming a continuation of the shape of the gun stock 10.

The intermediate cushioning member 14 is preferably provided with one or more air pockets 23, the air pockets 23 being closed at one end by the supporting plate 12 and at the other end by the shoulder engaging cushion 13. The supporting plate 12, intermediate cushion and shoulder engaging member may all be secured together by cementing, vulcanizing or other appropriate means and it will thus be observed that a plurality of air pockets 23 are provided from which the air may escape only through the pores of the sponge rubber body 14. The foregoing structure provides a pad of great resiliency which is adapted to resist the recoil more effectively due to the presence of the air pockets which entrap air to be forced out through the pores of the rubber.

15 The air pockets 23 are preferably provided with a plurality of resilient bodies 24 which are capable of coming into engagement with the supporting plate 12 and shoulder engaging member 13 at different stages in the deformation or distortion of the pad. The resilient bodies 24 may take many different forms, depending upon the size and shape of the air pockets 23, but in the embodiment shown in Figure 3 a plurality of cylindrical air pockets 23 are provided with substantially cylindrical rubber plugs 24, the rubber plugs being of slightly smaller diameter than the air pockets 23.

The rubber plugs 24 are preferably made of different sizes in order to adapt the resiliency of the recoil pad to the individual needs of any marksman and in the present embodiment, which is to be regarded as exemplary, the upper and lower plugs or resilient bodies 24 are slightly shorter than the

length of their air pockets 23. The next two resilient bodies 25 and 26 may be made still shorter and the middle resilient body 27 may be the shortest of all, assuming that it is desired to provide a pad having the greatest resiliency or give adjacent the resilient body 27.

It should, of course, be understood that if the individual marksman prefers the "feel" of a recoil pad which is stiffer at the center and which is not resilient or soft at other points, this result can be readily accomplished by providing resilient bodies of appropriate length at the points desired. In general the resiliency or softness of the pad is increased by providing shorter resilient bodies 24 at any particular point and in some cases the resilient bodies may be omitted entirely from certain air pockets.

The operation of the recoil pad shown in Figures 1 to 5 is as follows: When the recoil pad is subjected to pressure between the shoulder of the marksman and the gun stock 10 on recoil of the gun, the pad is distorted from its usual shape and the major portion of the distortion takes place in the intermediate rubber cushion 14. The shoulder engaging portion 13 of the pad is also capable of permitting some distortion but is preferably of sufficient stiffness to distribute the force of the recoil over a greater area of the cushion 14. As the shoulder engaging portion 13 is forced toward the supporting plate 12, the air entrapped in the air pockets 23 is forced out through the pores of the sponge rubber 14 at a very high velocity, the air tending to increase the resilient resistance of the cushion 14. As soon as the shoulder engaging portion 13 approaches a certain stage of distortion relative to the supporting plate 12, the longest resilient bodies 24 come into engagement with the supporting plate 12 and shoulder engaging member 13 and tend to increase the resistance of the pad. At another subsequent stage of distortion of the pad the resilient bodies 25 and 26 may come into engagement with the walls of their air pockets and finally the shortest resilient body 27 may come into operative engagement with the walls of its air pocket to increase the resistance of the pad.

It will thus be observed that the resilient bodies 24 and 27 are adapted to provide a pad of predetermined characteristics capable of meeting the individual needs of any marksman and the resilient bodies come into operative engagement with the other parts of the pad at different stages in the distortion of the pad, thereby regulating the resiliency at any predetermined point. If the marksman wishes to protect any particular point upon his shoulder, such as a spot which tends to become sore, he may do so by diminishing the length or size of the rubber plugs 24 at that point in the pad, thereby making the

pad softer at that point. It should be noted also that the resulting characteristics of the pad are due in part to the shapes of the respective resilient bodies and their air pockets, and the resilient bodies themselves diminish the volume of air in the air pocket.

In the embodiment shown in Figures 6 and 7 the air pocket 23 is an elongated air pocket having rounded ends 28 and the pocket extends across substantially the entire end of the gun stock. In this embodiment the resilient body 24 comprises a rubber body having an outline 29 substantially complementary to the shape of the air pocket 28. One side 29 of the resilient body 24 in Figures 6 and 7 may be flat, while the opposite side 30 may be provided with a concave or convex surface, spaced somewhat from the shoulder engaging portion 13 of the pad.

In the form shown in Figure 6 the resilient body 24 is thicker at the middle, thereby increasing the resistance of the pad at the center after the pad has been deformed a predetermined amount, that is, after the shoulder engaging portion 13 is compressed sufficiently to engage the rubber body 24. If it is desired to make the center of the recoil pad softer the rubber body or filler 24 may be cut down to the concave shape illustrated at 31.

It will thus be observed that I have invented an improved recoil pad including a resilient casing and one or more resilient bodies carried thereby, by means of which the resilient characteristics of the pad may be regulated or predetermined at any point and adapted to suit the individual "feel" of the user. The present invention is of peculiar importance to marksmen who find that some certain portion of the shoulder requires additional protection or greater softness of the pad and in general the present recoil pad is adapted to give a maximum of satisfactory results in every individual case.

While I have illustrated and described two specific embodiments of my invention I do not wish to be limited to the precise details of construction set forth but desire to avail myself of all changes within the scope of the appended claims.

Having thus described my invention what I claim as new and desire to secure by Letters Patent of the United States is:

1. In a recoil pad for guns, a resilient cushion comprising a supporting member, a shoulder engaging member, an intermediate cushioning structure comprising a body formed with an air pocket and a resilient member carried in said pocket and formed to produce a pad of predetermined resilient characteristics.

2. In a recoil pad for guns, a resilient cushion comprising a supporting member, a shoulder engaging member, an intermediate cushioning structure comprising a body

formed with a plurality of air pockets, and resilient members carried in said pockets and adapted to be distorted in succession at various stages of distortion of said pad to adapt the pad to the individual feel of the marksman.

3. A recoil pad for guns comprising a rear supporting wall, and a front shoulder engaging wall of resilient material, an intermediate resilient member having an air pocket extending longitudinally of said pad, and a resilient member of predetermined thickness for engaging between said walls at a predetermined amount of distortion of said pad, to suit the needs of an individual marksman.

4. A recoil pad for guns comprising a rear supporting wall, and a front shoulder engaging wall of resilient material, an intermediate resilient member having a plurality of air pockets, and a plurality of resilient members carried in said pockets for engagement between said walls at different stages of distortion of said pad.

5. In a recoil pad for guns, the combination of a resilient casing forming a recoil pad, with resilient means carried within said casing and adapted to engage the walls of said casing upon distortion of said pad, said resilient means being shaped to produce a predetermined resiliency of said pad by the engagement of said resilient means with the walls of said casing at different stages of distortion of said pad.

6. In a recoil pad, the combination of a resilient casing with a plurality of resilient bodies of different size for engaging the walls of said casing at different stages of distortion of said pad.

7. In a recoil pad for guns the combination of a support with a resilient rubber cushion carried by said support and having a closed air pocket, said cushion comprising porous rubber adapted to throttle the passage of air from said pocket to improve the resilient characteristics of said pad.

8. In a recoil pad for guns the combination of a support with a resilient rubber cushion carried by said support and having a closed air pocket, said cushion comprising porous rubber adapted to throttle the passage of air from said pocket to improve the resilient characteristics of said pad, and a resilient rubber body in said pocket for engaging the walls of said pocket after said pad is deformed a predetermined amount.

9. In a recoil pad for guns the combination of a support with a resilient rubber cushion carried by said support and having a closed air pocket, said cushion comprising porous rubber adapted to throttle the passage of air from said pocket to improve the resilient characteristics of said pad, and a resilient rubber body in said pocket for engaging the walls of said pocket after said

pad is deformed a predetermined amount, said body having a predetermined outline for engaging at different parts of the pad wall at different times to adapt the resilient characteristics to the feel of the user.

10. In a recoil pad for guns the combination of a support with a resilient rubber cushion carried by said support and having a closed air pocket, said pocket extending transversely to the stock of the gun upon which the pad is used, and said cushion comprising porous rubber adapted to throttle the passage of air from said pocket to improve the resilient characteristics of said pad.

11. In a recoil pad for guns the combination of a support with a resilient rubber cushion carried by said support and having a closed air pocket, said pocket extending transversely to the stock of the gun upon which the pad is used, and an elongated resilient body in said air pocket, said resilient body being thickened adjacent the middle of the pad to cause initial engagement with the wall of said pocket at the middle of the pad.

12. In a recoil pad for guns, the combination of a resilient rubber body having a plurality of air pockets with a plurality of resilient bodies in said pockets for changing the resilient characteristics of the pad, said bodies being graduated in length to engage the walls of said pockets at different degrees of distortion.

In witness whereof, I hereunto subscribe my name this 27 day of August, 1929.

ALBERT H. AMMANN.
